Filed Apr. 1, 1968, Ser. No. 11,240

Term of patent 14 years

U.S. Cl. D34—15

Int. Cl. D21—04

FIG. 2

FIG. 4

FIG. 1 is a perspective view of a dragon head for playground apparatus in accord with my new design,
FIG. 2 is a front elevational view.

FIG. 3 is an elevational view of the right side, the left side being similar in appearance, and
FIG. 4 is a top plan view.

The broken line showing of playground apparatus in FIG. 1 and fragmentary showings in FIGS. 3 and 4 are for illustrative purposes only.

I claim:

The ornamental design for a dragon head for playground apparatus, substantially as shown and described.
